CLAIM

The ornamental design for a milk frother, as shown and described.

DESCRIPTION

FIG. 1 is a front perspective view of a pedestal portion of a milk frother, showing my design, showing the pedestal portion independently to show aspects of the design not visible when combined;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front perspective view of a cup portion of the milk frother, showing the cup portion independently to show aspects of the design not visible when combined;

FIG. 10 is a rear perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a front perspective view of the cup and the pedestal portion of the milk frother, shown assembled;

FIG. 18 is a rear perspective view thereof;

FIG. 19 is a front elevation view thereof;

FIG. 20 is a rear elevation view thereof;

FIG. 21 is a left side elevation view thereof;

FIG. 22 is a right side elevation view thereof;

FIG. 23 is a top plan view thereof; and,

FIG. 24 is a bottom plan view thereof.

The broken lines in the drawings are shown for the purpose of illustrating parts of the milk frother that form no part of the claimed design.
